US0D1044787S

(12) **United States Design Patent** (10) Patent No.: **US D1,044,787 S**
(45) Date of Patent: ** *Oct. 1, 2024

(54) **MOBILE PHONE**

(71) Applicant: **BEIJING XIAOMI MOBILE SOFTWARE CO., LTD.**, Beijing (CN)

(72) Inventors: **Jueguan Mo**, Beijing (CN); **Haoxia Wu**, Beijing (CN); **Shengyu Gong**, Beijing (CN); **Xu Wei**, Beijing (CN); **Yin Zhu**, Beijing (CN)

(73) Assignee: **BEIJING XIAOMI MOBILE SOFTWARE CO., LTD.**, Beijing (CN)

(*) Notice: This patent is subject to a terminal disclaimer.

(**) Term: **15 Years**

(21) Appl. No.: **35/517,466**

(22) Filed: **Feb. 15, 2023**

(80) **Hague Agreement Data**

Int. Filing Date: **Feb. 15, 2023**

Int. Reg. No.: **DM/229240**

Int. Reg. Date: **Feb. 15, 2023**

Int. Reg. Pub. Date: **Jun. 9, 2023**

(30) **Foreign Application Priority Data**

Aug. 31, 2022 (CN) 202230574836.8

(57) **CLAIM**

The ornamental design for a mobile phone, as shown and described.

DESCRIPTION

FIG. 2.1 is a front view of a first embodiment of a mobile phone showing our new design.

FIG. 2.2 is a back view thereof;

FIG. 2.3 is a left side view thereof;

FIG. 2.4 is a right side view thereof;

FIG. 2.5 is a top plan view thereof;

FIG. 2.6 is a bottom plan view thereof;

FIG. 2.7 is a front perspective view thereof;

FIG. 2.8 is a rear perspective view thereof;

(Continued)

FIG. 4.1 is a front view of a second embodiment of a mobile phone showing our new design;
 FIG. 4.2 is a back view thereof;
 FIG. 4.3 is a left side view thereof;
 FIG. 4.4 is a right side view thereof;
 FIG. 4.5 is a top plan view thereof;
 FIG. 4.6 is a bottom plan view thereof;
 FIG. 4.7 is a front perspective view thereof; and
 FIG. 4.8 is a rear perspective view thereof.
 The broken lines in the drawings show portions of the mobile phone that form no part of the claimed design.
